(57) **CLAIM**

The ornamental design for a mobile wire spool carrier, as shown and described.

DESCRIPTION

FIG. 1 is a front right perspective view of the mobile wire spool carrier showing our new design;

FIG. 2 is a front elevational view of the mobile wire spool carrier;

FIG. 3 is a rear elevational view of the mobile wire spool carrier;

FIG. 4 is a right side view of the mobile wire spool carrier;

FIG. 5 is a left side view of the mobile wire spool carrier;

FIG. 6 is a top plan view of the mobile wire spool carrier;

FIG. 7 is a bottom plan view of the mobile wire spool carrier; and,

FIG. 8 is another front right perspective view of the mobile wire spool carrier.

The broken lines shown in FIGS. 1 through 8 are for the purpose of illustrating portions of the mobile wire spool carrier and form no part of the claimed design. The spools shown in broken lines in FIG. 8 are for the purpose of showing environmental structure and form no part of the claimed design.
